UNITED STATES PATENT OFFICE.

JOHN SCHUMACHER, OF LOS ANGELES, CALIFORNIA.

PLASTER BOARD.

Application filed November 14, 1921. Serial No. 514,914.

This invention relates to a plaster board formed of a plaster core and covering sheets. Such boards are commonly used for covering walls in building constructions.

5 It is the primary object of this invention to provide a board which is reinforced at the edges, and with the covering sheets so arranged that they are securely attached to the plaster core at their edges, thereby preventing the sheets from being accidentally pulled away from the plaster in handling. It is another object of this invention to provide a board so reinforced at its edges, that it will not chip.

15 Other objects and corresponding accomplishments will be apparent from the subjoined specification and drawing accompanying the specification, in which:

Fig. 1 is one type of board embodying my 20 invention shown in perspective; and Fig. 2 is a still further modified form.

Referring particularly to Fig. 1, a board is shown comprising a plaster core 19 between covering sheets 20 and 22. I prefer 25 to use a moist unstable plastic substance, which may be fed between continuously advancing sheets of paper. The side edges of the paper sheets are turned inwardly and the product in its soft condition is cut into 30 initial lengths. In setting and drying, the paper adheres to the plaster core 19.

In Fig. 1, the edges of the paper are shown forming return bends with rectangular corners and the free edges of the upper 35 and lower sheets adjacent one another. The side edges are in effect completely covered forming a finished edge so that trimming is not necessary. The edges of the paper are embedded in the plaster core and form a reinforcement which strengthens the board. The edge of the board is covered by a tough 40 sheet preventing chipping. Furthermore, there is no opportunity for the board to start peeling at the edge, as the edge of the 45 paper is embedded in the plaster.

In Fig. 1 the invention is shown embodied in a board having rabbeted edges provided with extensions which may be lapped. In effect the ends of the board are halved. The construction is obtained by turning one end 50 of one cover inwardly short of the other. It

is obvious that it is immaterial whether the sheets are parallel to each other in the core, or whether they enter the core at angles. However, with the construction shown in Fig. 1 the sheet should be bent to form halves which will interlock and form smooth joints. Fig. 2 shows a construction similar to Fig. 1, but the edges are bent to form bevelled dove-tails. Thus, a board will have one edge in the form of a bevelled recess to receive the tongue.

What I claim is:

1. A plaster board comprising a body of plaster composition having rabbeted edges, 65 paper attached to and covering both sides of the main body and one side of each of the rabbeted edges, and paper covering the opposite sides of each of said rabbeted edges and embedded in the body of plaster composition, substantially as described.

2. A plaster board comprising a body of plaster composition having a tongue at a side edge to form an interlocking joint with the complementary edge of an adjacent 75 board, each face of said body having an adhering cover sheet of fibrous material, one of said cover sheets being extended over said tongue and embedded in the body of the plaster composition.

3. A plaster board comprising a body of plaster composition having a stepped or rabbeted edge, each face of said body having a covering of fibrous material, one of said coverings being folded to enclose the extended portion of said rabbeted edge and being embedded in the body of the plaster composition.

4. A plaster board comprising a body of plaster composition having an extension at 90 each side edge to form an interlocking joint with the corresponding edge of an adjacent board, each face of said body having an adhering cover sheet of fibrous material, one of said cover sheets being folded around 95 the adjacent extension and extended inwardly a distance into the body of plaster composition.

In witness that I claim the foregoing I have hereunto subscribed my name this 8th day of November, 1921.

JOHN SCHUMACHER.
